FLOW RESTRICTOR

Carl F. Alsing, Springfield, Mass., assignor to
Westinghouse Electric & Manufacturing Com-
pany, East Pittsburgh, Pa., a corporation of
Pennsylvania

Application August 31, 1936, Serial No. 98,754

3 Claims. (Cl. 62—1)

My invention relates to a flow restrictor for restricting the flow of fluid from a high to a low pressure region, and particularly to a flow restrictor for restricting and lowering the pressure of liquid refrigerant passing from the condenser to the evaporator of a refrigerating system.

It is an object of my invention to provide an improved flow restrictor of the capillary passage type in which clogging of the passage by lint and dirt is practically eliminated.

It is another object of my invention to provide an improved flow restrictor of the capillary tube type for use in a refrigerating system in which refrigerant and lubricant are in contact with the windings of the motor driving the compressor.

These and other objects are effected by my invention as will be apparent from the following description and claims taken in connection with the accompanying drawing and forming a part of this application, in which:

Fig. 1 is a diagrammatic view of a compressor refrigerating system embodying my invention; and,

Fig. 2 is an enlarged view of the inlet end of the flow restrictor shown in Fig. 1 as a capillary tube.

Referring to the drawing for a detailed description of my invention, numeral 11 designates a sealed casing containing a motor 12 and a refrigerant compressor 13. Refrigerant is drawn from the interior of the casing 11 through a compressor inlet 14 and compressed refrigerant is forced through an outlet conduit 15 to a condenser 16 wherein it is condensed by the air driven over the condenser by a fan 17. Liquid refrigerant is conveyed from the condenser 16 through a conduit 18 to a flow restricting and pressure reducing device generally indicated at 19 (Fig. 1). Refrigerant is admitted through the flow restricting device 19 to an evaporator 21, wherein liquid refrigerant at low pressure vaporizes and absorbs heat. Refrigerant vapor is withdrawn from the evaporator 21 through a conduit 22 by the action of the compressor 13 and enters the interior of the sealed casing 11, where it comes in contact with windings 23 of the motor 12. The motor windings are usually insulated with cloth or paper and shreds of the insulation may be present in the refrigerant.

The flow restricting device 19 preferably comprises a helically coiled tube 24 of considerable length and having a passage 25 therein of relatively small bore so as to restrict the flow of liquid from the condenser to the evaporator 21.

Such devices are referred to by some in the refrigeration art as capillary tubes. One end 26 of the tube 24 extends into the evaporator 21, and the inlet end 27 of the tube extends into a fitting 28 having a chamber 29 into which liquid refrigerant from the condenser 16 is conveyed through the conduit 18.

In refrigerating systems employing capillary tube type flow restricting devices, the inlet end of the small passageway in the tube may clog 10 because small shreds of lint from the insulation on the motor, pieces of dirt and the like catch on the sharp edges of the tube, crosswise of the opening of the passage 25. After a few such particles adhere to the inlet of the tube, other particles add rapidly to those already caught and eventually bridge and clog the passage, necessitating opening the system to clean the tube, which is obviously very expensive and troublesome.

In order to obviate these difficulties, I have 20 rounded the inlet edge of the tube 24, as shown at 31. I have, furthermore, tapered the outer surface of the tube at the inlet end as shown at 32. By so forming the capillary tube 24, shreds 25 of lint, dirt and the like, when they contact the rounded edge and tapered sides 32, slide off the edge and either pass through the passage 25 lengthwise, as shown at 33, or pass to the outside of the tube 24 along the tapered sides 32. Furthermore, by rounding the edge of the tube 30 24, its flow characteristics are improved because turbulence at the inlet thereof is reduced.

From the foregoing it will be apparent that I have provided an improved flow-restricting device which will not clog up with lint and dirt, and which is designed for use with a hermetically sealed motor-compressor unit wherein the refrigerant is in contact with the insulated windings of the motor.

While I have shown my invention in but one 40 form, it will be obvious to those skilled in the art that it is not so limited, but is susceptible of various changes and modifications without departing from the spirit thereof, and I desire, therefore, that only such limitations shall be 45 placed thereupon as are imposed by the prior art or as are specifically set forth in the appended claims.

What I claim is:

1. In a refrigerating system, the combination 50 of a condenser and an evaporator in which refrigerant is successively condensed and evaporated, said condenser forming a part of the high pressure region of the system, and a device for restricting the flow of refrigerant between the 55

- condenser and the evaporator, said device comprising a tube having a restricted flow passage therein, the inner edge of the tube at the inlet end having inwardly converging walls, forming an entrance to said passage, and the material between the wall of the passage and the outer wall of the tube at the inlet end being rounded, whereby a smooth surface is provided at the inlet end, said high pressure region of the refrigerating system having a portion of larger flow area than said tube, said inlet end of the tube extending into said portion of larger flow area.
2. A capillary tube for a refrigerator system, which system includes an evaporator and a condenser in which refrigerant is successively evaporated and condensed, said condenser forming a portion of a high pressure region of the refrigerating system, said capillary tube having a relatively restricted bore of uniform diameter for controlling the flow of liquid refrigerant from the condenser to the evaporator, the walls of the bore being curved outwardly adjacent the extremity of the tube, said curved walls meeting at a point adjacent the entrance of the tube, whereby a smooth surface is provided at said inlet end, said high pressure region of the refrigerating system having a portion of larger cross sectional area than the area defined by the outer circumference of said tube, and said inlet end of the tube extending into the portion of the relatively larger flow area.
3. In a refrigerating system, the combination of an evaporator and a condenser in which refrigerant is successively evaporated and condensed, said condenser forming a portion of the high pressure region of the refrigerating system, a motor and a compressor for circulating refrigerant to the evaporator and condenser, a sealed casing for enclosing the motor and compressor and containing some of said refrigerant in contact with both the motor and compressor, and means including a capillary tube having a relatively restricted bore of uniform diameter for controlling the flow of liquid refrigerant from the condenser to the evaporator, the walls of the bore being curved outwardly adjacent the extremity of the tube, and the outer walls of the tube being curved inwardly adjacent the extremity of the tube, said curved walls meeting at a point adjacent the entrance of the tube, whereby a smooth surface is provided at said inlet end, said high pressure region of the refrigerating system having a portion of larger cross sectional area than the area defined by the outer circumference of said tube, and said inlet end of the tube extending into the portion of the relatively larger flow area.

CARL F. ALSING.
